BOTTLE OR SIMILAR ARTICLE

Charles K. Huthsing, Jr., Libertyville, Ill.; N. Evelyn Huthsing, executor of said Charles K. Huthsing, Jr., deceased

Filed Sept. 29, 1970, Ser. No. 25,255

Term of patent 14 years

Int. Cl. D9—01

U.S. Cl. D9—40

FIG. 1 is an elevational view of a bottle or similar article embodying my new design;

FIG. 2 is an elevational view looking from the right of FIG. 1;

FIG. 3 is an elevational view looking from the left of FIG. 1;

FIG. 4 is a top plan view; and

FIG. 5 is a bottom plan view thereof.

The side opposite that seen in FIG. 1 is a mirror image of the side shown.

I claim:

The ornamental design for a bottle or similar article, as shown and described.
